UNITED STATES PATENT OFFICE.

FRITZ BRÜCK, OF OSNABRÜCK, GERMANY.

SUBMARINE CONTACT-MINE.

1,021,089.

Specification of Letters Patent. Patented Mar. 26, 1912.

Application filed September 16, 1910. Serial No. 532,269.

To all whom it may concern:

Be it known that I, FRITZ BRÜCK, a subject of the German Emperor, residing at Osnabrück, Germany, have invented certain new and useful Improvements in Submarine Contact-Mines, of which the following is a specification.

Safety ignition arrangements for contact mines, especially offensive mines, for rendering such mines "safe" or insensitive when they have broken from their anchorage, and depending on variability of water pressure at different depths are well known; such arrangements are generally made to employ hydrostatic plates of diverse constructions which are adapted to break the ignition or fuse circuits as soon as the water pressure has fallen below a predetermined amount. These constructions are subject to the objection that the difference in pressure of the water upon a mine which is anchored at a small distance from the surface from that upon a drifting mine is so small that, especially in rough seas, the safety devices cannot be depended upon with certainty and uniformity even if constructed with the greatest care and accuracy.

The subject of the present invention is a device for rendering mines of the above referred to character safe by utilizing the tension produced in the member connecting the mine casing and the anchor by the buoyancy of said casing, one or more springs being interposed in this member, or above or below the same, between the anchor and the casing, which spring (or springs) is stressed by the tensile force so as to insure that the mine shall be armed, while on the cessation of the tension the mine is rendered safe. Instead of springs, one or more counter weights may be used in which there is produced by the tension a variation in position, which continues so long as the tension is maintained. As the buoyancy of the mine casing in good mines is equivalent to at least 70 to 80 kilograms, but is frequently much greater, there is available an operative force of such magnitude that the previously indicated unreliability of working no longer obtains.

Besides rendering the mine safe after it has broken loose from its anchor, it is also possible by means of my invention to meet the requirement, especially necessary with

offensive mines, that the mine shall be safe so long as it is rigidly connected with the anchor, for example, while it is on board ship before being laid. To this end the connection between mine casing and anchor, before the mine is laid, is of such a character that the springs or counter weights are free from strain.

My invention also comprises means for allowing the person who lays the mine to bring the mine casing, after it has been set under water, to the surface, or to separate it entirely from its connection with its anchor. The mine is thus rendered safe and may be handled without danger thus avoiding the necessity of discharging or sinking it in order to render it harmless.

It is of importance that variations in the condition of the springs or in the position of the weights should not follow too closely the initiation and interruption of the tension in the connecting member between the mine and the anchor by changes in buoyancy of the mine casing. Unless this condition is satisfied then while an offensive mine rigidly connected with its anchor is on board the mine-laying ship, or when it is being transported for the purpose of being laid, said mine might readily be armed, even if only for a brief period of time, by being shaken or upset. Similarly, after a mine is adjusted under water, a hostile ship might accidentally run upon the mine in such manner that the mine would be depressed for an instant before an ignition cap would be struck, the mine would thus be safe at the moment of true contact and fail of its purpose. To avoid these several difficulties I provide in my invention that alterations in the condition of the springs or in variations in the position of the counter weights shall take place slowly. For this purpose brakes are provided for retarding within suitable limits the rate at which variations in the condition of the springs or in the position of the weights take place.

Finally, it is of importance to provide that when the mine is kept long under water the variations in the condition of the springs or in the position of the weights shall not be interfered with by deposits of animal or vegetable matters. Having regard to the powerful force available, this object may be realized by forming the surfaces, which are

pressed together for limiting the movement representing variation in the condition of the springs or in the position of the weights, with notches and spikes so as to sever or 5 penetrate the foreign bodies.

In the accompanying drawings which illustrate the invention, Figure 1 is a vertical elevation, partly in section along the line 1—1 of Fig. 3, showing a mine buoy or 10 casing rigidly coupled with its anchor by a soluble connection; the mine represented is an offensive mine of which the reel or drum for winding the anchor rope is fixed to and rises with the mine casing; the device for 15 arming the mine and rendering it safe is in such position that the ignition circuit is broken. Fig. 2 shows the mine casing fixed to the anchor by an anchor rope, adjusted to hold said casing at the desired depth below 20 the water level; the device for rendering the mine safe and arming it is here in such position that the ignition circuit is closed. For the sake of clearness the mine casing and the anchor are shown broken away. 25 Fig. 3 is a vertical section on the line 3—3 of Fig. 1. The anchor is here shown with my improved devices for releasing and floating the mine casing. Fig. 4 is an end view (taken from the left, Fig. 3) showing the 30 box attached to the mine casing which contains the anchor rope reel as also the spring suspension.

In the drawings *f* denotes the mine casing which rests on a supporting frame *p* fixed 35 to the anchor *g* which anchor is adapted to be moved along rails, the casing being held in this position before laying the mine by a connection *a* *q*, provided with a soluble block *s*, the ends of the connecting links 40 *a*, *q* being respectively connected to the anchor and to the box *f*¹. When the mine is laid the block *s* is dissolved by the action of the water and the casing *f* by reason of its buoyancy rises from the anchor until it 45 reaches the depth below the water level at which it has been arranged to be floated or held; at this depth the means dependent upon hydrostatic pressure (not shown), is employed to actuate a clamping device 50 attached to the box *f*¹ so as to grip and prevent any further unwinding of the cable. This box *f*¹ contains the reel or drum *d*¹ *d*² for the anchor rope *d*; it is located beneath the casing *f* and is mounted on springs *f*² 55 by means of lateral lugs, which springs are carried by stirrups *f*³ rigidly connected with the casing. The box is so mounted on these springs that it is ordinarily pressed upwardly by the springs *f*² against the bottom 60 of the casing, the springs being chosen to exert a substantially greater force than is required to balance the weight of the box with the drum, rope and appurtenances. This position of the parts is represented in 65 Figs. 1, 3 and 4. The box *f*¹ also carries a

double armed lever 2. The inner end of the lever is pivoted to the casing *f* while the outer end carries a contact pin 3 which is guided in a switch box 4 attached to the box *f*¹. The two contacts 5 and 6 in this box 4 70 are included in the electrical circuit comprising the conductor 9, the lead caps 7 and the fuse 8.

In the embodiment of the invention shown in the drawings the mine is fired by the impact of a ship destroying one of the lead caps 7 whereby a battery is brought into operation the flow of current from which through the ignition circuit 9 brings the fuse 8 to incandescence. Accordingly, any 75 interruption of the ignition circuit renders the mine safe. To interrupt the circuit, the pin 3 is brought into the position shown in Figs. 1 and 4 in which it no longer connects electrically the two contacts 5 and 6. As 80 soon, however, as a downward pull is exercised on the box *f*¹ in excess of the pressure of the springs *f*², as is the case when tension is produced in the rope *d* by reason of the buoyancy of the mine casing, the box *f*¹ is 85 withdrawn from the mine casing and the springs *f*² are compressed, as shown in Fig. 2. The pin 3 then connects the contacts 5 and 6 and the fuse circuit is closed 90 so that the mine is armed. As soon as the tension in the rope *d* is discontinued by the 95 breakage or release of the anchor rope, the springs *f*² again expand and press the box *f*¹ against the mine casing, so that the pin 3 is again withdrawn from the contacts 5 and 6 100 and the fuse circuit is opened or interrupted.

Fig. 2 shows the mine casing and the box *f*¹ separated from one another by the tension due to buoyancy. Should, in course of time, when the mine is under water, vegetable or 105 animal matter such as seaweed or shellfish accumulate between the box *f*¹ and the mine casing, the teeth or spikes 11 provided on the box will cut or penetrate these foreign bodies when the springs are released after 110 the force of buoyancy has been suspended and thereby insure that the mine shall be rendered safe.

The retarding brakes which insure that the springs *f*² shall slowly alter their position consist, in the present case, of pistons 12 rigidly connected with the stirrups *f*³, over which pistons cylinders 13 attached to the box *f*¹ and filled with liquid are arranged to travel. The pistons 12 are each 120 formed with only a small aperture 14 through which liquid can pass from the one side to the other side of the piston.

In order to be able to collect the mines in a manner which will not be dangerous there 125 is employed a releasing or floating attachment attached to the anchor (Fig. 3). On being thrown overboard the mines are connected together by means of connecting lines 15 and 16 secured to rings 17 and 18. The 130

one ring 17 is fixed to the anchor while the other ring is connected to the releasing or floating device. This latter is so arranged that when tension is applied to the line 16 5 the anchor rope *d* is detached from the anchor, even though the tension is less than is represented by the weight of the anchor. On collecting the mines therefore first the anchor rope is detached and then the anchor 10 itself is lifted.

If it is not desired to detach the anchor rope but only to float the mine so that the mine casing floating on the surface shall remain connected with the anchor, the anchor 15 rope is held by the releasing device not at its end but at a part of the anchor rope which is, say, about ten yards from the end, while the end of the anchor rope is fastened to the anchor in any suitable manner. On the actuation 20 of the releasing device therefore the ten yards of rope are freed and the mine rises to the surface.

The releasing device itself, which may be of variable construction, consists in the 25 present example of a double-armed lever 19 pivoted to the anchor, to an arm of which lever the ring 18 is attached by means of the line 16. The other arm of the lever 19 presses against a jaw 21 pivoted on a fulcrum 30 20, which jaw 21 clamps the anchor rope between it and an eccentric clamp 22. The greater the tension of the anchor rope, the more tightly the rope is clamped by the eccentric 22 and the more securely is it retained. By pulling the line 16, the lever 19 35 is turned downwardly with the arm bearing on the jaw 21 and the jaw 21 can turn around the fulcrum 20. In this way, the anchor rope is freed. In order that during 40 the laying of the mine the lever shall not be prematurely moved out of its position in consequence of the line 16 being pulled, a soluble safety device 23 is provided which permits movement of the lever only after 45 said device has been dissolved by the seawater and this, of course, will be some time after the mine has been laid.

I have described a preferred embodiment 50 of my invention but many variations of design may be made without departing from

the spirit of the invention which I have set forth in the following claims:

I claim—

1. In a submarine mine of the class described having a casing provided with an ignition circuit, an anchor and an extensible connecting cable, the combination of a circuit closing device in said ignition circuit a reel to carry said cable, said reel being movable relatively to said casing and means uniting said reel to said casing and arranged to engage said circuit closing device, said means being adapted to change its position with reference to the casing with change of tension in the cable so as to actuate said circuit closing device.

2. In a submarine mine of the class described having a casing provided with an ignition circuit, an anchor and an extensible connecting cable, the combination of a circuit closing device in said ignition circuit, a reel to carry said cable, said reel being movable relatively to said casing, springs between and engaging both said reel and said casing, and means operatively connected both with said reel and said casing to actuate said circuit closing device when the relative position of reel and casing is changed.

3. In a submarine mine of the class described having a casing provided with an ignition circuit, an anchor and an extensible connecting cable, the combination of a circuit closing device in said ignition circuit, a reel to carry said cable, said reel being movable relatively to said casing, springs between and engaging with said reel and said casing, means operatively connected to both said reel and said casing to actuate said circuit closing device when the relative position of reel and casing is changed, and braking means for retarding the rate at which said relative position is changed.

In testimony whereof I have hereunto set my hand in the presence of two subscribing witnesses.

FRITZ BRÜCK.
